ELECTRON DISCHARGE DEVICE

Hans Mahl, Berlin, Germany, assignor to General
Electric Company, a corporation of New YorkApplication May 28, 1938, Serial No. 210,612
In Germany June 2, 1937

5 Claims. (Cl. 250—162)

The invention relates to electron discharge devices, and more particularly, to electron lens systems in cathode ray tubes wherein mesh electrodes are provided.

- 5 In the past, it was proposed to use mesh electrodes in connection with electron-optical systems. The data of earlier times have been collected in the book by Brüche and Scherzer, "Geometrische Elektronenoptik" (Berlin 1934). 10 But as explained there, (compare page 44, note 4), not only the author of the book, but also other experts have been convinced of the uselessness of mesh electrodes in electron-optical ray-passages. Hence, every kind of mesh electrode, whether two- 15 fold meshes disposed one behind the other for attaining a double layer, (Fig. 31 of the book cited), or single mesh, for attaining a focal spot (Brennfleck)—(Fig. 82 of this book), or simple acceleration mesh electrodes (compare the article 20 by Henneberg and Recknagel in the "Zeitschrift für Technische Physik", vol. 16, p. 232, note 15, 1935), has been avoided in electron-optical systems, and in view of those cited and other objections to the use of mesh electrodes, such as have 25 repeatedly been made of late years by experts, the state of the art can be assumed to be such, that mesh electrodes do not come into the question 30 has electron lens elements in electron-optical systems.
- 30 In connection with the experiments, on which the present invention is based, this generally existing prejudice has been ignored and the surprising result was attained, that the introduction of a mesh into the electron-optical ray-passage 35 excised no unfavorable influence on the reproduction, if only the mesh electron be made fine enough. Since these experiments have once been carried through, the explanation for this result appears simple. Whilst indeed, hitherto several 40 mesh electrodes disposed closely one behind the other have been used for attaining double layers for electron-optical purposes and, from the unfavorable results attained therewith, the general 45 uselessness of mesh electrodes was a foregone conclusion, according to the invention only one element of the electron lens is developed as mesh electrode in the electron-optical ray passage. In this case, the path of the rays shows, in fact, only those disturbances which occur at single mesh 50 electrode, and which need not lead to any considerable disturbance of the picture. On the other hand, the case is different, when several mesh electrodes are provided in the ray passage one behind the other. Since the meshes of the 55 different mesh electrodes do not lie on correspond-
- ing points of the ray passage, mutual influencing of (interference with) the mesh electrodes occurs, which renders the picture useless.
- The employment of one mesh electrode, as lens-electrode in electron optical devices, has various 5 advantages. It is, as a matter of fact, difficult to make the electron optical copy of great cathode surfaces, particularly of flat cathodes. The reason for this is that the electron optical aberrations increase sharply, as the distance from the 10 optical axis increases. On the other hand, owing to the nature of the potential field, either the electron exit is restricted to a very small scope or, if electrons can indeed pass out of a considerable scope, then generally the electrons passing 15 out at a greater distance from the axis will fall on the focusing electrodes, which operate as apertured diaphragms or stops. These disadvantages can be avoided by the employment of suitably shaped, fine mesh electrodes, or of very thin 20 foil electrodes which are equally pervious to the electrons.
- The invention will be more particularly described with reference to the drawing, in which Fig. 1 shows diagrammatically one simple form 25 of the invention, wherein the focusing mesh electrode has substantially the same curvature as the focusing electrostatic field, while
- Figs. 2 through 6 show varying modifications 30 of the electron lens system shown in Fig. 1.
- In Fig. 1, K indicates the electron emitting, 35 large-surface cathode from which the electrons are focused, A is a mesh electrode which serves as an anode, and L the luminescent screen. The potentials can be selected so that for instance, as compared with K, A has a potential of 5000 volts and L has the same or a higher potential. In the figure there are drawn in further the equi-potential lines and the passage of the ray, starting from 40 a point of the cathode. The lens effect of the device can easily be seen from the potential field and the passage of the ray.
- While it was assumed, in connection with Fig. 1 45 that the mesh electrode was developed as lens electrode, and represents, apart from the cathode and luminescent screen, the only lens electrode, in Fig. 2 the case has been illustrated, in which the mesh electrode serves solely for the attainment of a high electron emission of the cathode. The mesh electrode N is here developed as a flat 50 one and disposed in front of the cathode K. For focusing, the three cylindrical electrodes Z₁, Z₂ and Z₃ have progressively increasing potentials. While these three electrodes may have potentials, for instance, of 300, 900 and 5000 volts as com- 55

pared with the cathode, the mesh electrode N has advantageously a higher voltage as compared with the cathode than the first cylinder, for instance 2000.

5 In most cases, however, the mesh electrode will be employed for the improvement or for the support of the lens field generated by the remaining electrodes. It can find employment in the same way, in combination with electric as also with 10 magnetic lenses. In Figs. 3 and 4 the employment of a mesh electrode N is provided for, in combination with a further cylindrical electrode A. The potential field, developing between the cathode K and the anode A is influenced by the 15 curve of the mesh electrode. In the case illustrated in Fig. 4, in which, owing to the effect of the mesh electrode in front of the cathode K, a collecting lens effect is attained, it may in some circumstances be desirable to impart to the mesh 20 electrode a concave curve with regard to the cathode, so that first a dispersing effect takes place. The collective effect, necessary for the focusing, can be generated through the field between the mesh electrode and the cylindrical 25 anode A.

The employment of a mesh electrode for the production of corrected electron lenses, offers special advantages. In this respect, the correction may refer to the geometrical faults (spherical 30 aberration and the like) or to the elimination of the chromatic fault. For the elimination of the chromatic fault, it is of importance that with mesh electrodes dispersing systems can be produced, while lenses working without mesh electrodes, as is known, always represent collecting 35 lenses, insofar as they are in field free space.

The possibility of the correction of a lens field, by imparting a suitable form, may be seen from Figs. 5 and 6. In Fig. 5 the uncorrected lens device is represented, in which the mesh electrode 40 has a hollow spherical form. Fig. 6 shows the same system, but corrected by a special formation of the mesh electrode.

It is, of course, self evident that the correction 45 of a system can only take place if, with otherwise unchanged potentials and with unchanged form and distance apart of the electrodes, there is imparted to the mesh electrode a certain form, a certain position with regard to the other electrodes and a certain potential as compared with the remaining potentials. The focusing system 50 in accordance with the invention can be employed everywhere, where the systems hitherto known have been employed, thus more particularly, with 55 cathode ray tubes, electron microscopes, in electron valves and the like.

As will be clear from the previous explanation, the devices, working with mesh electrodes in accordance with the invention, and cited as embodiments as examples, have yet a further property, which distinguishes them from the devices of the known kind, provided with mesh electrode lenses. Since between the mesh electrode and the next electrode (cathode or anode) there is a considerable space, the effect of the mesh electrode 60 on the potential field can be divided into two constituent parts, into one undesired distortion, effective in the direct proximity of the

mesh electrode, owing to the field penetrating through the meshes and into an influencing of the potential. In the examples given, the second effect preponderates, owing to the high speed of the electrons at the mesh electrode and 5 owing to the great intermediate space between the mesh electrode and the remaining electrodes. It is possible, that this fact alone, or in combination with the above mentioned avoidance of interferences, with the employment of one mesh 10 electrode only, guarantees the usefulness of the devices described. In the first case, the employment of several mesh electrodes at a sufficient distance from each other might be possible. Since with foils no penetration of the field takes place, 15 all the devices hitherto proposed with mesh electrodes can have thin foil electrodes substituted for the mesh electrodes.

Having described my invention, what I claim is:

1. An electron focusing system comprising a 20 planar cathode, a cylindrical electrode positioned normal to said cathode, one end of said cylindrical electrode surrounding said cathode, and a curved mesh electrode at least partially surrounded by said cylindrical electrode and normal 25 to the axis of said electrode.

2. An electron focusing system comprising a planar cathode, a cylindrical electrode positioned normal to said cathode, one end of said cylindrical electrode surrounding said cathode, and a curved mesh electrode normal to the axis of said cylindrical electrode and partially surrounded by 30 said cylindrical electrode.

3. An electron focusing system comprising a 35 planar cathode, a cylindrical electrode positioned normal to said cathode, one end of said cylindrical electrode surrounding said cathode, and a curved mesh electrode normal to the axis of said cylindrical electrode and completely surrounded by 40 said cylindrical electrode.

4. A cathode ray tube comprising a symmetrical planar cathode, a cylindrical anode in register with said planar cathode, said cylindrical anode having its axis coinciding with the axis of symmetry of said cathode, said anode being adapted 45 to be supplied with positive potential relative to said cathode to produce an electrostatic field having axially symmetrical uni-potential surfaces, and a curved mesh focusing electrode in register with said cathode and at least partially surrounded by said cylindrical anode, said mesh electrode having a curvature substantially identical with one of said unipotential surfaces.

5. A cathode ray tube comprising a planar cathode, a target electrode, said target electrode 55 and said cathode being symmetrical about a common axis, cylindrical anode means positioned intermediate said cathode and said target electrode to produce an electrostatic field having uni-potential surfaces of predetermined curvature between said cathode and said target electrode, and a curved mesh electrode normal to said common axis and positioned intermediate said cathode and said target, said mesh electrode having a curvature substantially the same as one of said 60 uni-potential surfaces.
